Patented Sept. 30, 1913.

UNITED STATES PATENT OFFICE.

PAUL BOHACEK, OF FRANKFORT-ON-THE-MAIN, GERMANY, ASSIGNOR TO MASCHINEN-FABRIK MOENUS A.-G., OF FRANKFORT-ON-THE-MAIN, GERMANY, A CORPORATION.

LEATHER-STAKING MACHINE.

1,074,348.

Specification of Letters Patent. Patented Sept. 30, 1913.

Application filed May 1, 1913. Serial No. 764,924.

To all whom it may concern:

Be it known that I, PAUL BOHACEK, a subject of the Emperor of Austria-Hungary, residing at 63 Moltke Allee, Frankfort-on-the-Main, in the Kingdom of Prussia and Empire of Germany, have invented new and useful Improvements in Leather-Staking Machines, of which the following is a specification.

10 This invention relates to leather staking machines having tools adapted to move to and fro and to coöperate similarly to pincers, use being made of clamping rolls arranged for traveling to and fro so as to 15 hold the leather lying freely upon a stationary apron.

With a view to rendering the leather staking device suitable not only for the simple staking operation, but also for boarding leather, the invention comprises two pairs of clamping rolls situated one in front and one at the rear of the staking blade for holding the leather, all the rolls or only some of them being actuated in such a manner that 20 during the traveling movement of the rolls just as much material is conducted behind the staking blade as there is material conducted away from the rolls situated in front of the staking blade. By this means there 25 will be no tension in the leather, which is bent on its passage over the blade. The requisites for a favorable staking action are therefore fulfilled by this arrangement, inasmuch as the leather receives in the main 30 only a single bend and is not subjected to tension, thus insuring the staking of even the most tender leathers.

In the accompanying drawing a preferred constructional form of the machine comprising 35 the improved leather holding device is represented in diagram, the tool consisting of a simple blade.

The leather or work 1 rests freely upon the apron 2 fixed to the transverse beam 3 and to the tension roll 3. In front and at the rear of the blade 9 which constitutes the tool are arranged pairs of clamping rolls 13, 14 and 13¹, 14¹. The rolls 13, 13¹ underneath the leather are for instance rotated by 40 the apron 2 in the direction indicated by arrows, inasmuch as the slides 10 carrying these rolls in conjunction with the staking

blade 9 attached to the lower staking arm 7 carries out the traveling movement. Above the leather or work are the clamping rolls 55 14, 14¹ which are likewise caused to travel, being fixed to the upper staking arm 6. These rolls are supported in swinging levers 15, which are drawn toward each other by a coil spring 15^a connecting them, and guide 60 rolls 16 journaled on the levers 15, contact with the cam disk 17 with the object of enabling both rolls 14, 14¹ to be displaced away from and toward the staking blade 9 and the boarding action to be varied. For 65 this purpose the cam disk 17 may be turned in any desired manner by means of a rod 18 either forward or backward. This allows the boarding action to be modified and therefore an individual treatment of different parts of the leather and kinds of leather 70 to be effected.

Of course the invention may be carried out in various ways apart from the constructional form represented in the drawing. Thus for instance it is altogether immaterial whether the blade 9 remains in its highest position between the rolls 14, 14¹ during the whole operation, or whether it is used for the formation of the fold of the 80 leather at the beginning of the working stroke and subsequently drawn back again. Moreover, either the upper or the lower clamping rolls, or all the clamping rolls together, may be driven. As actuating means 85 use may be made of toothed or frictional gear wheels, or the like, besides the apron 2. Furthermore, an arrangement may be employed in which the staking blade is fixed together with the upper rolls to the upper 90 staking arm, or it may also be moved independently in any desired manner.

I claim:

1. In a leather staking machine an apron fixed at one end to a cross beam, carrying 95 rollers beneath said apron, a tension roller to which the other end of said apron is secured, a staking blade extending upwardly from between said carrying rollers, hinged levers above said apron, clamping rollers on 100 said levers and means to reciprocate said clamping rollers toward and away from each other.

2. In a leather staking machine an apron

fixed at one end to a cross beam, carrying rollers beneath said apron, a tension roller to which the other end of said apron is secured, a staking blade extending upwardly from between said carrying rollers, hinged levers above said apron, clamping rollers on

levers adapted to engage said cam and a rod to adjust said cam, as specified.

In testimony whereof I affix my signature in the presence of two witnesses.

PAUL BOHACEK.
